(57) **CLAIM**

The ornamental design for an electronic device, as shown and described.

DESCRIPTION

FIG. 1 is a front, top, right perspective view of a first embodiment of an electronic device;

FIG. 2 is a front view thereof;

FIG. 3 is a back view thereof;

FIG. 4 is a left-side view thereof;

FIG. 5 is a right-side view thereof;

FIG. 6 is a top view thereof;

FIG. 7 is a bottom view thereof;

FIG. 8 is a front, top, right perspective view of a second embodiment of an electronic device; the crosshatched pattern shown on the views of the second embodiment represents a woven fabric, and is understood to be distributed uniformly over the surface of the claimed design upon which the pattern occurs;

FIG. 9 is a front view thereof;

FIG. 10 is a back view thereof;

FIG. 11 is a left-side view thereof;

FIG. 12 is a right-side view thereof;

FIG. 13 is a top view thereof;

FIG. 14 is a bottom view thereof;

FIG. 15 is a front, top, right perspective view of a third embodiment of an electronic device;

FIG. 16 is a front view thereof; the lattice pattern shown in the small openings on the bottom side of the electronic device represents an acoustic mesh fabric;

FIG. 17 is a back view thereof;

FIG. 18 is a left-side view thereof;

FIG. 19 is a right-side view thereof;

FIG. 20 is a top view thereof;

FIG. 21 is a bottom view thereof;

(Continued)

FIG. 22 is a front, top, right perspective view of a fourth embodiment of an electronic device; the crosshatched pattern shown on the views of the fourth embodiment represents a woven fabric, and is understood to be distributed uniformly over the surface of the claimed design upon which the pattern occurs;

FIG. 23 is a front view thereof; the lattice pattern shown in the small openings on the bottom side of the electronic device represents an acoustic mesh fabric;

FIG. 24 is a back view thereof;

FIG. 25 is a left-side view thereof;

FIG. 26 is a right-side view thereof;

FIG. 27 is a top view thereof; and,

FIG. 28 is a bottom view thereof.

The broken lines depict portions of the electronic device that form no part of the claimed design.
